UNITED STATES PATENT OFFICE.

LOUISE PFUHL, OF ROCHELLE PARK, NEW JERSEY.

DESIGN FOR A PLATE OR SIMILAR ARTICLE.

Application filed April 23, 1929. Serial No. 30,984. Term of patent 7 years.

To all whom it may concern:

Be it known that I, LOUISE PFUHL, a citizen of the United States, residing at 70 Passaic Street, Rochelle Park, in the county of Bergen and State of New Jersey, have invented a new, original, and ornamental Design for Plate or Similar Article, of which the following is a specification, reference being had to the accompanying drawing, forming part thereof.

The figure is a plan view of a plate or similar article showing my new design.

The design being a repetition of a unitary

design, with the exception that one of the units is slightly modified, a segment only of the unitary design and a segment of the slightly modified unitary design are illustrated in the drawing; it being understood that the unitary design at the left of the drawing is merely repeated in the two blank segments to complete the entire design.

I claim:

The ornamental design for a plate or similar article substantially as shown and described.

LOUISE PFUHL.
